US0D1086719S

(12) **United States Design Patent** (10) **Patent No.:** **US D1,086,719 S**
(45) **Date of Patent:** **** Aug. 5, 2025**

(54) **LID FOR STORAGE BOX**

- (71) Applicant: **L&F PLASTICS, CO., LTD.**, Miaoli County (TW)
(72) Inventor: **Mu-Chuan Hsu**, Miaoli County (TW)
(73) Assignee: **L&F Plastics, Co., Ltd.**, Miaoli County (TW)

(**) Term: **15 Years**

(21) Appl. No.: **29/872,060**

(22) Filed: **Mar. 6, 2023**

(30) **Foreign Application Priority Data**
